SELF-RELEASING BATTERY TERMINAL CLAMP

Hugo E. Seils, Chicago, Ill., assignor of twenty-six and two-thirds per cent to Charles M. Peters, Lansing, Ill.

Application April 9, 1940, Serial No. 328,709

1 Claim. (Cl. 173—259)

This invention relates to a self-releasing clamp and more particularly to a clamp adapted to be readily connected with and disconnected from an object such as the protruding terminal of a storage battery. While the invention is particularly applicable to a battery terminal clamp of the kind which is normally permanently connected to a cable and adapted to be releasably connected with a storage battery terminal to provide an electrical connection between the battery and the cable, it should become apparent as the description proceeds that the invention in its broader aspects is equally applicable to other specific uses.

The primary object of the invention is the provision of a clamp construction suitable for the purpose above indicated which, by means of relatively simple and easily constructed arrangements, the clamp may be tightly secured to a terminal, for example, and readily disengaged therefrom regardless of the corrosion or other bonding action which has taken place between the terminal and the clamp. While various arrangements have heretofore been proposed to accomplish the general object set out, none have been particularly successful in practice and an analysis of the prior construction for analogous devices shows either that the cost of construction is prohibitive or that they possess insufficient durability to withstand the adverse conditions under which such devices are used. It is accordingly a more specific object of the invention to provide a clamp having the characteristics above indicated but which may be economically constructed and which possesses advantages of ruggedness and durability not inherent in comparable devices heretofore in existence.

These and other objects and advantages of the invention will become apparent from a consideration of the following detailed specification and the accompanying drawing wherein there is specifically disclosed a preferred embodiment of the invention.

In the drawing:

Figure 1 is a top view of a clamp constructed in accordance with the teachings of the invention;

Figure 2 is a side view of the clamp of Figure 1 showing the clamp as applied to a conventional terminal of a storage battery; and

Figure 3 is a fragmentary side view of a portion of the clamp of Figure 1 before the clamp is assembled for operation.

In the drawing, provided for purposes of illustration and wherein similar reference numerals

are used to designate corresponding parts throughout the various views, reference numeral 10 indicates generally a clamp body which may be cast, forged or otherwise suitably formed, of metal possessing the desired coefficient of electrical conductivity and suitably resistant to corrosive actions. Body 10 is provided with a shank 11 having a centrally disposed bore 12 extending inwardly from the outer end thereof and, in accordance with usual practice, a cable 13 may have its end soldered or otherwise suitably secured in the bore. Outwardly of the body 10 cable 13 may be provided with suitable insulation 14. At the end of the shank 11 opposite the cable 13—14 the body 10 is bifurcated into two arms 15 and 16, the first of which is heaved somewhat at its outer end and provided with a threaded transverse aperture 17. The inner surfaces of the arms 15 and 16 where they leave the shank 11 are rounded about an axis normal to the plane of the arms and these rounded surfaces, together with the rounded inner end of the shank 11, provided an expansible cylindrical bore 18 which is adapted to fit over and about a round member to which a clamp is to be applied, such as the terminal 19 of a storage battery 20.

The outer end of arm 16 is constructed with the shape shown in full lines in Figure 3. A rounded aperture 21 of substantial size is provided in the arm 16 adjacent its outer end and the width of the arm is arcuately increased at 22 about the aperture 21. Aperture 21 is of sufficient size to allow the shank of a cap screw 24 with a flange 25 encircled thereabout to pass through the aperture. In assembling the clamp the shank and flange of the cap screw are passed through the aperture 21 and the end of the screw is screw threaded into the threaded aperture 17 of the arm 15. The turning of the screw is continued until the head 26 of the screw engages the outer face of the arm 16 in which position of the parts the flange 25 will be inward of the inner face of the arm 16. The arm 16 is now collapsed about the shank of the screw between the flange 25 and the head 26 and this may be accomplished by positioning the arm 16 edgewise between an anvil and a hammer with the arcuately shaped edges 22 engaged by the anvil and the hammer. Or, in lieu of the above, the arm 16 may be collapsed by a suitable pressing operation. Whether collapsed by hammering or pressing, the arm 16 changes in shape from that shown by full lines in Figure 3 to that shown by dotted lines in Figure 3 and

by full lines in Figures 1 and 2. It should be observed that the arm is elongated and that the round aperture 21 is changed to an elongated aperture which is designated 31 on the drawing. By referring to Figure 2, it should be apparent that the width of the elongated aperture 31 is substantially equal to the diameter of the shank 24 of the cap screw and that, therefore, as the cap screw is screwed out of the threaded aperture 17, the flange 25 will engage the inner face of the arm 16 and positively force the arms 15 and 16 apart. For maximum strength the flange 25 is preferably forged integrally with the shank of the cap screw but it should be obvious that other expedients may be resorted to to provide the flange on the screw shank.

The operation of the above specifically described embodiment of the invention should be readily apparent. With the clamp assembled in the manner indicated and as shown in Figures 1 and 2 of the drawing, the screw 24 is first unscrewed to spread the arms 15 and 16 a sufficient distance apart to allow the bore 18 to be received over the battery terminal 19 or other object to which it is to be applied and then by rotating screw 24 in a clockwise direction the arms 15 and 16 will be drawn tightly together and the bore 18 tightly clamped about the terminal 19 or other object. When the clamp is to be removed from the terminal or other object, the screw 24 is rotated counter-clockwise and as the screw backs out of the threaded aperture 17 the flange 25 will engage the inner face of the arm 16 and positively move the arms 15 and 16 apart. This opening movement will be transmitted to the bore 18 and the same will be readily loosened from the terminal or other object. This feature is of particular advantage in connection with the storage battery use as corrosion invariably takes place about the terminals of such batteries which often binds the terminal and clamp together substantially as a unitary member. The clamp may be applied and released from the battery terminal post with the aid of but one tool—a wrench to engage the head 26 of the cap screw and as there is no danger of slipping between the tool and the battery the danger of injury to the latter is eliminated.

As the arms 15 and 16 are moved away from each other they assume a divergence relative to each other and since the screw 24 is snugly received in the aperture 17 the cap end of the screw moves outwardly relative to the bore 18 and shank 24 and towards the outer end of the arm 16. By reason of the elongated aperture 31 this readjustment of the relative positions of the parts may be effected without undue binding or stress of the parts, thus contributing substantially to the efficient operation of the clamp.

Conversely, as the arms 15 and 16 are moved together the head end of the screw will move slightly inwardly along the arm 16.

It should now be apparent that this invention accomplishes the objects initially set out. Since the flange 25 may be incorporated as an integral part of the cap screw or otherwise ruggedly secured to the shank of the screw by reason of the fact that the screw and flange may be completely constructed before the same is incorporated in the clamp structure, the clamp may be very rugged and durable. The assembling of the parts involves only the collapsing of the arms 15 and 16 and, as this may be accomplished by a simple blow of the hammer, definite economies may be effected in the production of the clamps. The clamp is operative to forcibly disengage the terminal engaging surface 18 from the terminal post or other object as well as to tightly clamp the surface thereto. This may be effectively accomplished irrespective of the variation in the diameter of the terminal post or other object since the clamping arms 15 and 16 may be moved towards and away from each other a considerable amount and, when so moved, undue binding in the apertures through which the cap screws pass or large bending stresses are not set up in the screw since the elongation of the aperture 31 allowing the head end of the screw to move relative to the arm 16 will relieve the binding and bending stresses.

The above specifically described embodiment of the invention should be considered as illustrative only as obviously many changes may be made therein without departing from the spirit or scope of the invention. Reference should accordingly be made to the appended claim in determining the scope of the invention.

Having thus fully described my invention what I claim is:

A clamp comprising in combination a unitary body having two relatively movable arms adapted to engage opposite sides of a member to which the clamp is to be applied, a threaded aperture in one of said relatively movable arms, the other of said relatively movable arms being initially provided with a large aperture intermediate its ends, a cap screw having a rigidly attached flange about its shank receivable through said enlarged aperture, the threaded end of said cap screw being screw threaded in said threaded aperture, said other of said relatively movable arms being swaged inwardly about said enlarged aperture whereby said enlarged aperture is elongated to an extent whereby the width of the elongation is substantially less than the diameters of the head and flange of said screw, said flange and head of said screw being on opposite sides of the said other of said relatively movable arms.
